UNITED STATES PATENT OFFICE.

CHARLES PIQUETTE MITCHEL, OF DETROIT, MICHIGAN.

SHOE RACK.

Application filed March 27, 1922, Serial No. 547,159. Renewed December 12, 1927.

This invention relates to an improvement in shoe racks and method of making the same.

One of the objects of my invention has been to simplify and cheapen the construction of shoe racks for use especially for keeping shoes off the floor in closets or the like.

Another object of my invention has been so to construct a shoe rack of this type that a plurality of them may readily be nested for shipping, with resultant economy for this purpose.

Another object of my invention is to construct a shoe rack which will have the upper and lower shoe supporting bars present a more or less flat surface to the sole of the shoe instead of a sharp edge.

Other objects of the invention will be obvious to those skilled in the art from the following description of a shoe rack embodying it.

Fig. 1 is a front elevation of a shoe rack embodying my invention.

Fig. 2 is a top plan view of the same.

Fig. 3 is a perspective view illustrating the application of one of the racks to a door.

Fig. 4 is a cross section on line 4—4 Fig. 3.

Figs. 5 and 6 illustrate a number of the racks nested for shipping.

Fig. 7 is a perspective view of a modified form of shoe rack embodying my invention.

Fig. 8 illustrates a blank of sheet metal in perspective from which one of my modified forms of shoe rack may be formed.

Fig. 9 illustrates the first blanking operation in the formation of the one piece shoe rack.

Fig. 10 illustrates the first bending operation on the blank.

Fig. 11 illustrates the second bending operation on the blank.

Fig. 12 illustrates a modified blanking operation in perspective.

Fig. 13 is a view in perspective of my modified form of shoe rack of the type shown in Fig. 12.

In the drawings 1 represents an upper bar preferably made of readily formable metal, such as cold roll flat wire. This bar is formed near either end with portions 1^a, 1^b bent at substantially right angles to a central portion 1^c and with portions 1^d, 1^e bent at substantially right angles to the portions 1^a and 1^b, respectively.

A lower bar 2 is formed with a central

portion 2^c, end portions 2^a, 2^b which are longer, substantially twice the length of the corresponding end portions 1^a, 1^b of the upper bar, and with portions 2^d, 2^e at right angles to the portions 2^a, 2^b, respectively. The portions 1^a, 1^b, 2^d and 2^e are preferably of the same dimensions. 3, 3' are vertical supports for the rack arranged at either end thereof and each preferably formed of a metallic material of the same character and size as the upper and lower bars 1 and 2. The portions 1^a, 1^b of the upper bar are secured in any suitable manner to the upper end of the vertical supports 3 and 3' respectively, whereas the portions 2^d, 2^e of the lower bar are likewise secured to the lower ends of said supports respectively. I have found a neat, simple, durable and economical method of making these connections to be by electric spot welding. When thus constructed, the shoe racks are relatively light in weight, neat in appearance and sufficiently rigid for all requirements.

It will be noted that the central portions of the bars 1 and 2 are horizontally disposed one above the other and in different vertical planes so that the heel of the shoe may be engaged and retained in position by the upper bar while the front part of the sole of the shoe rests upon the upper surface of the lower bar.

It will thus be seen by comparing Figs. 1 and 2 that the vertical supports 3, 3' connecting the end portions 1^a, 2^a and 1^b, 2^b, respectively, are horizontally spaced apart intermediate the shoe supporting portions a greater distance than the width of the shoe supporting portions plus the thickness of the end portions. Thus other shoe racks of the same size can have either the shoe supporting portion 2 and the end portions 2^a, 2^b or the portion 1 and the end portions 1^a, 1^b readily insertable between the vertical supports 3, 3' of another shoe rack and the shoe racks of the same size can be nested for shipment.

I have found it convenient to attach my improved shoe rack directly to the back of closet doors, for example as shown in Fig. 3 in the drawing. This may readily and quickly be done by means of screws 4 extending through drilled holes in the supports 3, 3' and entering the woodwork of the door. When thus mounted I have found that the shoes will be properly supported and will

not be dislodged from the rack by any ordinary slamming of the door. Preferably the cold drawn steel wire has rounded edges which facilitate the use and handling of the rack.

By constructing my improved shoe rack substantially in skeleton form, it will be noted that I may readily nest pluralities of the same for economy of space in shipping or storing. In Figs. 5 and 6 I have shown several of my improved shoe racks thus nested. In Figs. 7 to 13 inclusive my invention is embodied in a rack formed from a single piece of sheet metal, preferably cold rolled sheet steel. Fig. 8 represents a blank of such metal. This blank is first subjected to a blanking operation after which it bears the shape illustrated in Fig. 9. In the next forming operation, preferably the ends of the blank are bent at right angles to the upper and lower bars as illustrated in Fig. 10, thus providing two center portions 4^c, 5^c of the same length with end bars 4^a, 4^b and 5^a, 5^b respectively. Next the connecting bars or supports 6 are bent substantially at right angles to the end sections 4^a, 4^b, 5^a, 5^b.

It will thus be seen that I have formed from a single piece of sheet metal a rack embodying my invention which, when attached to a flat vertical surface such as a door, will provide upper and lower bars 4^c, 5^c respectively in different vertical planes, since the end bars 4^a, 4^b connecting the upper bar 4^c with the supports 6 are shorter than the end bars 5^a, 5^b connecting the lower bar 5^c with the said supports.

Should it be desired to form shoe racks embodying my invention by this process and in this manner of relatively thin sheet metal and yet have the supports sufficiently rigid, the same may be accomplished by providing flanges for the various bars which in the finished rack are bent at right angles to the planes of the bars proper and rearwardly so as to be practically concealed. In Fig. 12 I have illustrated in perspective a blank thus formed in the first operation and in Fig. 13 in perspective one of the racks thus completely formed.

To those skilled in the art to which this invention relates many alterations in construction and widely differing embodiments and applications of my invention will suggest themselves without departing from the spirit and scope thereof. My disclosures and description herein are purely illustrative and are not intended to be in any sense limiting.

What I claim is:

1. A shoe rack including a pair of relatively narrow spaced members each having a shoe supporting portion and end portions extending at an angle to the shoe supporting portion, said members being disposed in different vertical planes, one above the other, 60 said end portions having outwardly extending flanges substantially parallel to the shoe supporting portion, vertical supports connecting the end flanges of each pair of said end portions, the portions of said supports 65 intermediate the shoe supporting members being spaced a greater distance apart than the width of the shoe supporting portions.

2. A shoe rack including a pair of relatively narrow spaced members each having a shoe supporting portion and end portions disposed substantially at right angles to the shoe supporting portions, said shoe supporting portions being disposed one above the other and in different vertical planes, 70 connecting members connecting the adjacent ends of said end portions, and means whereby the said connecting members are spaced apart a greater distance than the width of the shoe supporting portion whereby said 75 shoe rack is readily nestable with other shoe racks of the same size.

3. A shoe rack including a pair of relatively narrow spaced members comprising shoe supporting portions and end portions 90 bent substantially at right angles to the shoe supporting portions, the end portions of the upper member being substantially shorter than the end portions of the lower member, said end portions being provided with end 95 flanges extending outwardly substantially at right angles to the end portions, and vertical supports each connecting a pair of said end flanges, the portions of the vertical supports intermediate the shoe supporting members being spaced a greater distance apart than the width of the shoe supporting portions.

4. A shoe rack including a pair of relatively narrow spaced members each having a shoe supporting portion and end portions 105 extending at an angle to the shoe supporting portion, said shoe supporting portions being disposed one above the other in different vertical planes, all of said end portions 110 terminating with flanges disposed in a plane substantially parallel to the shoe supporting portions, and connecting members connecting the adjacent flanges of said spaced members and serving as supports for the rack.

In testimony whereof I affix my signature.

C. PIQUETTE MITCHEL.
